UNITED STATES PATENT OFFICE.

ELI J. SCHROCK, OF GOSHEN, INDIANA.

WINDMILL.

SPECIFICATION forming part of Letters Patent No. 291,783, dated January 8, 1884.

Application filed February 3, 1883. (No model.)

To all whom it may concern:

Be it known that I, ELI J. SCHROCK, a citizen of the United States of America, residing at Goshen, in the county of Elkhart 5 and State of Indiana, have invented certain new and useful Improvements in Windmills, of which the following is a specification.

This invention relates to windmills; and it consists in the peculiar construction and 10 arrangement of the same, whereby the wheel and vane may be thrown out of line, and a brake applied to the wheel to keep it stationary, substantially as will be hereinafter more fully set forth, and pointed out in the 15 claims.

In order to enable others skilled in the art to which my invention appertains to make and use the same, I will now proceed to describe its construction and operation, referring 20 to the annexed drawing, which represents a perspective view of my invention.

A represents the wheel composed of a flanged or socketed central hub, *a*, in which are secured the radial arms *a'*. To these 25 arms are secured, by clips *a''* and castings *a'''*, two concentric rings, *b* *b'*, in which are secured the wings or sails *b''* of the wheel. The socketed hub *a* is, upon its rear side, formed or provided with a ring, *c*, the purpose of which will be presently seen. This 30 wheel A is mounted upon a shaft or axle, *c'*, journaled in one side of the turn-table or swiveled head B.

B represents a large casting forming the 35 turn-table or head of the mill, and is formed with a hollow neck, *B'*, swiveled upon the tower or frame C, as seen in the drawing. This head B is also provided with an opening, *d*, in its center, in which, secured upon 40 the inner end of the shaft *c'*, is a disk, *c''*, provided with a wrist-pin connected by a pitman, *c'''*, with the pump-rod D, reciprocating vertically through the hollow neck *B'*. This rod D is formed with a double bend, *d'*, as seen 45 in the drawing.

Upon the rear side of the head B are cast two lugs, *e* *e'*, to which are pivoted the arms E E. Supporting the vane, and at right angles with these lugs, near the lower end of

the head, are cast lugs *e' e''*, in which is journaled a rod, *f*, having its inner end bent, as seen at *f'*, to bear against the ring *c*, upon the wheel when the rod is turned, and so form a brake.

Near the outer end of the rod is secured 55 an arm, F, provided with a weight, *f''*, and the extreme outer end of the rod is bent up, as seen at *f'''*, and formed with an eye, connected by a link, *g*, to the arms E of the vane. 60

To the weighted arm F is also secured a cord, *h*, running over a pulley, *h'*, in the head, and thence to the ground or to any point desired.

In operation, the parts of the mill are normally in the position shown by the drawing, and the head with its wheel and vane turns freely upon the tower with variations of the wind.

When it is desired to stop the mill, the 70 cord *h* is pulled, raising the arm F and turning the rod *f*, which, by its connecting-link, turns the vane and throws the wheel out of the wind. At the same time the cranked arm *f'*, at the opposite end of the rod, bears against 75 the ring *c* upon the wheel, and effectually brakes it.

I am aware that it is not new to provide a windmill with a brake-ring to engage with a brake, and do not claim the same, broadly; 80 but

What I do claim, and desire to secure by Letters Patent, is—

1. In a windmill, the wheel A, provided with a ring, *c*, and pivoted to the head or 85 turn-table B, in combination with a crank-rod, *f*, journaled in lugs *e' e''*, and formed with a brake at one end, adapted to engage with the ring *c*, and leaving its extreme outer end bent up, as seen at *f'''*, and formed with 90 an eye connected to the vane, whereby when the rod is turned the wheel is thrown out of the wind and the brake applied, substantially as shown and described.

2. In a windmill, the combination, with 95 the wheel A, having a ring, *c*, and journaled on the swiveled head B, and connected by a pitman, *c'''*, with the pump-rod D, of the

rod *f*, formed with a brake, *f'*, on one end, and connected by the link *g* with the vane *E*, the weighted arm *F*, rigidly secured to the brake-rod, and the operating-cord *h*, and 5 pulley *h'*, all constructed and arranged to operate substantially as described and shown, and for the purpose set forth.

In testimony whereof I affix my signature in presence of two witnesses.

ELI J. SCHROCK.
